UNITED STATES PATENT OFFICE.

RICHARD D. HARRIGAN, OF LEADVILLE, COLORADO.

TELEPHONE-BELL.

SPECIFICATION forming part of Letters Patent No. 558,385, dated April 14, 1896.

Application filed November 5, 1895. Serial No. 567,968. (No model.)

To all whom it may concern:

Be it known that I, RICHARD D. HARRIGAN, of Leadville, in the county of Lake and State of Colorado, have invented new and useful 5 Improvements in Telephone-Bells, of which the following is a full, clear, and exact description.

This invention relates to bells for telephones; and the object is to provide a simple and quick-acting device whereby the bell will continue to be sounded after the main 10 circuit shall have been opened or cut out—for instance, at the main office—and also to ring a bell located at a distance from the telephone.

The invention consists in the construction and novel arrangement of parts, as will hereinafter appear, and be particularly pointed out in the claims.

Reference is to be had to the accompanying drawing, forming a part of this specification, in which the figure is a diagrammatic view of devices embodying my invention.

Referring to the drawing, A designates a 25 gong secured to the telephone-casing A'.

A² is an electromagnet, and A³ is a bell-hammer having an armature a on its pivoted shank portion, coating with the electromagnet. A spring a', secured at one end to the 30 hammer-shank and at the other end to the casing, serves to draw the armature from the electromagnet.

The electromagnet is located in a main circuit comprising a wire 1, leading directly to the electromagnet, a wire 2, leading to a contact-pin 3, a portion 4 of the hammer-shank, which is designed to engage with said pin and serve as a circuit-closer, and a wire 5, leading from the portion 4 of the hammer-shank 40 to the electromagnet.

B is a circuit-closer for closing an auxiliary circuit connected with the telephone-casing and comprising wires 7 8, connected, respectively, with the main wires 1 2 and with contact-points b b', which are here shown as mercury-cups; but I do not limit my invention to this form of contact-points, as ordinary metal fingers or plates will answer the purpose. In the auxiliary circuit is located a 45 battery B'.

The circuit-closer B is here shown as made in the form of an angle-lever pivoted at its

angle to a bracket b² and having a horizontal portion provided with contact-fingers b³ b⁴, adapted to engage with the contact-points b b', 55 and the closer has a vertically-disposed member b⁵, which, when the closer is in open position, bears against a stop-pin b⁶ on the casing. This stop-pin b⁶ is so located as to allow the upper portion of the member b⁵ to lie in close 60 proximity to the bell-hammer A³ when the same is in its normal position away from the gong.

In lieu of the pin b⁶ or in connection therewith I may employ an adjustable stop for the 65 circuit-closer B. The adjustable stop is here shown as a set-screw b⁷, extended through a tapped hole in an arm extended from the bracket b² and impinging against the closer.

In operation when the circuit is closed 70 through the main circuit the electromagnet will draw the hammer against the bell, and upon the return movement of the hammer under the influence of the spring a' the hammer will strike the member b⁵ of the closer B 75 and cause it to rock on its pivot and bring the fingers b³ b⁴ into engagement with the contact-points b b', thus closing the auxiliary circuit comprising the battery B'. When in this condition, and after the main circuit shall 80 have been opened at the central office, the gong will be continuously sounded, or until the parts are returned to their normal position by disengaging the fingers b³ b⁴ from the mercury or similar contact-points b b'. I also 85 contemplate the closing of a circuit by means of the closer B, whereby a bell located at a distance from the telephone may be sounded, and to this end I show a bell B², which may be located at any desired point, and this bell 90 is contained in a circuit comprising a battery B⁸ and wires 9 10, which are in engagement with the contact-points b b'. It is obvious that this last-described circuit may be omitted or it may be employed alone, the main 95 object being to set a bell in operation after the first ringing of the telephone-bell. For the purpose of the claims this last-described circuit may also be termed an "auxiliary" circuit.

Having thus described my invention, I claim as new and desire to secure by Letters Patent—

1. In a telephone, a gong, a hammer there-

for, a main electric circuit for operating the hammer, an auxiliary circuit comprising a battery, wires connected with the main circuit-wires, and contact-points, and a closer 5 for said auxiliary circuit comprising a lever having its members arranged substantially at right angles to each other, one of the members being provided with contact-points to engage the contact-points of said auxiliary 10 circuit, and the other member adapted to be engaged by the hammer, substantially as specified.

2. In a telephone, the combination with an alarm device operated by a main electric cir-

cuit of an auxiliary circuit, wires having connection with the main circuit-wires, a battery in the auxiliary circuit, contact-points, a closer for said auxiliary circuit comprising an angle-lever having a horizontal portion provided with contact-fingers to engage the contact-points, and a vertically-disposed member adapted to be engaged by the hammer to operate said circuit-closer and a stop for said closer, substantially as specified. 15 20
